UNITED STATES PATENT OFFICE.

PERCY G. ABRAMS, OF PHILADELPHIA, PENNSYLVANIA.

CORD-FASTENING DEVICE.

1,055,503.

Specification of Letters Patent.

Patented Mar. 11, 1913.

Application filed December 7, 1911. Serial No. 664,388.

To all whom it may concern:

Be it known that I, PERCY G. ABRAMS, a citizen of the United States, residing at Philadelphia, in the county of Philadelphia and State of Pennsylvania, have invented certain new and useful Improvements in Cord-Fastening Devices; and I do declare the following to be a full, clear, and exact description of the invention, such as will 10 enable others skilled in the art to which it appertains to make and use the same.

This invention relates to improvements in cord fastening devices.

One object of the invention is to provide 15 a device of this character having an improved construction and arrangement of cord receiving mechanism whereby both ends of a cord may be securely fastened without tying.

20 A further object is to provide a cord fastening device which will be simple, strong, durable and inexpensive in construction, efficient and reliable in operation and well adapted to the purpose for which it is de- 25 signed.

With these and other objects in view, the invention consists of certain novel features of construction, and the combination and arrangement of parts as will be more fully 30 described and claimed.

In the accompanying drawings; Figure 1 is a perspective view of a package tied with a string, the ends of which are secured by my improved fastening device; Fig. 2 is an 35 enlarged central longitudinal sectional view of the fastener having the ends of the cord engaged therewith; Fig. 3 is a perspective view of the fastener showing one end of the cord engaged therewith and the position of the parts before the other end of the cord is 40 fastened; Fig. 4 is a perspective view of the inner side of the fastener; Fig. 5 is a cross section through the cord attaching end of the fastener.

45 My improved cord fastener comprises a body portion 1 which may be of any suitable shape and is here shown as of rectangular oblong form. The fastener is constructed of sheet metal and has formed therein a longitudinally disposed slot 2 one end of which terminates in a V-shaped cord receiving notch or recess 3, the purpose of which will be hereinafter described. Near the opposite 50 end of the body 1 is formed an upwardly extending tongue 4, said tongue being preferably formed from the metal cut in form-

ing the slot 2 and bent outwardly from the body 1 as shown in Fig. 3 of the drawing. At the opposite end of the body 1 from that in which the tongue is located and in the inner side of the body is formed a central longitudinally disposed groove or recess 5 the purpose of which will be hereinafter described. The edge of this end of the metal on each side of the groove 5 is bent or folded back against the under side of the body 6 on each side of the groove to form stop lugs 6 while the edge of the metal forming the groove 5 is bent inwardly to form a reinforcing bead 7, which, together with the 70 lugs 7 strengthen and reinforce this end of the fastener.

In using my improved fastener one end of the cord has formed therein a knot and said knotted end of the cord is secured by 75 engaging the same with the V-shaped notch 3 in the end of the slot 2 of the fastener and passing the cord beneath the end of the body 1 and in engagement with the groove 5 between the stop lugs 6 whereby when the 80 body is placed in position on the package to be tied, this end of the cord will be securely held and this end of the plate prevented from slipping laterally or turning on the cord. After this end of the cord has 85 been thus secured the same is passed around the package in the direction of the length of the body 1 and is passed around the tongue and thence around the package in the other direction, the end of the cord then 90 being again brought into engagement with the tongue and wrapped around the latter one or more times after which the tongue is bent downwardly into the slot 2, thus 95 clenching and securely fastening this end of the cord.

From the foregoing description taken in connection with the accompanying drawings the construction and operation of the invention will be readily understood without requiring a more extended explanation.

Various changes in the form, proportion and the minor details of construction may be resorted to without departing from the principle or sacrificing any of the advantages of the invention as claimed.

Having thus described my invention, what I claim is;

A cord fastener comprising a flat strip of metal with a longitudinal portion struck therefrom to provide a tongue and a slot, the tongue being bent vertically upward at

one end of the slot, the slot being extended to form a contiguous V shaped notch, one end of the strip having a plurality of slits to provide lugs and a reinforcing member, said 5 lugs and reinforcing member being bent inwardly to contact with the body of the strip, said reinforcing member and body portion above the reinforcing member being depressed upwardly to provide a groove between the inwardly bent lugs, and said

tongue adapted to bend downwardly in curved form above the slot whereby to form a fastening for the cord.

In testimony whereof I have hereunto set my hand in presence of two subscribing 15 witnesses.

PERCY G. ABRAMS.
